UNITED STATES PATENT OFFICE

ROY K. RUNYON, OF SPOKANE, WASHINGTON, ASSIGNOR OF ONE-HALF TO JOHN CARTMELL, OF SPOKANE, WASHINGTON

DUST COLLECTOR

Application filed August 19, 1929. Serial No. 386,833.

My invention relates to dust collectors and more particularly to a dust collector that is adapted to be installed on a motor vehicle and connected with the air intake of the carburetor thereof whereby the dust is removed from the air before it is sucked into the engine. Certain objects of the invention are to provide baffle means for forcibly projecting the air against a pool of oil whereby the heavier particles of dust are removed. Other objects are to provide a plurality of baffle plates having felt linings and metal lathings having pockets that catch the finer particles of dust when the air is sucked through the carburetor. Further objects are to provide certain additional novel details of construction as hereinafter set forth.

With the above and other objects in view which will appear as the description proceeds, the invention consists of the novel construction, adaptation, combination and arrangement of parts hereinafter described and claimed. These objects are accomplished by devices illustrated in the accompanying drawings; wherein:—

Figure 1 is a view in side elevation showing a portion of a motor vehicle with my device mounted thereon and connected with the carburetor thereof;

Fig. 2 is a view in exterior perspective of the dust collector;

Fig. 3 is an enlarged view in perspective showing a section of one of the baffle partitions;

Fig. 4 is a view in vertical section taken substantially on a broken line 4, 4 of Fig. 2; and

Fig. 5 is a view in horizontal section taken on a broken line 5, 5 of Fig. 4.

Referring to the drawings throughout which like reference numerals designate like parts, the numeral 5 indicates a housing having a cover 6 hinged thereto at 7 and arranged to be locked in the closed position by a thumb screw 8. A gasket 9 or other packing is placed between said housing and cover to make this part of the device air-tight for reasons hereinafter apparent.

The housing 5 may be secured to the vehi-

cle by means of screw carrying lugs 10. Referring to Fig. 1 of the drawings, the device is ordinarily mounted on the dash or other convenient place in the forward part of the vehicle where it may be reached by the driver or operator thereof. A rubber hose 11 or other flexible connection extends from the air intake of the carburetor 12 to an outlet connection 13 of the lid 6 and an intake 14 for said lid provides means whereby air is drawn through the device at each suction stroke of the vehicle engine as will be understood.

An inner casing 15 fits snugly within the housing 5 and is provided with an upper flange 16 which fits over the upper edge of said housing and is held in place by the lid 6. Both ends of said casing are open and the lower end is contracted by deflecting the lower edge portion inwardly to form a flange 17. A main baffle partition 18 for said casing extends downwardly from the joiner of the intake 14 and outlet 13 in a forward slantwise direction to a point adjacent said flange baffle thus forming a restricted passage 19 therewith.

A plurality of curved baffle partitions 20 are disposed in spaced relation across said casing to form a number of conduits 21 that communicate with the outlet 13. Thus, when the air is sucked into the intake 14 it passes downwardly through the restricted passage 19 and is thereby projected with some force against a pool of oil 22 in the bottom of the housing 5 from whence it is deflected upwardly through said conduits to the carburetor. The impact of the air with the oil will remove the larger particles of dust and the means for removing the smaller particles of dust from the air will now be described.

Referring particularly to Fig. 3 of the drawings, the baffle partition 18 as well as the baffles 20 are set in channel bars 23 that are secured to the sides of the casing 15. The baffle 18 comprises a sheet metal backing 24 against which a felt pad 25 is placed and a metal lathing 26 of well known construction is secured against said pad. Pockets 27 are formed by the apertures in said lathing whose lower edges are bent outwardly thus pro-

viding effective means for collecting the finer particles of dust from the air when it is projected thereagainst as indicated by the direction arrows in Fig. 4 of the drawings.

5 The baffles 20 are similar in construction to the baffle 18 with the exception that the felt pads 25 are placed against both sides of the metal backings 24. The lathing 26 is likewise placed on both sides thereof against the 10 pads and the upper edges of the pockets 27 are bent outwardly for the purpose of catching the finer particles of dust from the air as it moves upwardly. By making these baffles curved it will be obvious that the pockets will 15 engage the air more readily. It will now be apparent that the fine dust is effectively caught in the felt pads and in the pockets while the air is sucked through the device. The metal backings 24 prevent the air from 20 passing through the baffles as will be understood.

When the baffles become saturated with dust the casing 15 may be removed and cleaned by submerging same in a bath of 25 gasoline. The pool of oil 22 may also be drained off through a drain plug 28 and replaced by clean oil, and a drain cock 29 may be used for the purpose of retaining the oil at the proper level if desired. It will now be 30 apparent that I have provided an effective means for removing dust from the air prior to its entry into the carburetor so that the fuel mixture will enter the vehicle engine in a clean condition.

35 Having thus described my invention, it being understood that minor changes in its construction may be resorted to without departing from its scope and spirit, what I claim and desire to secure by Letters Patent of the

40 United States is:—

1. A dust collector comprising a housing, a lid pivoted to the housing, air-tight gasket connecting means between the lid and housing, an air intake and outlet for the lid, an 45 inner casing open at both ends, the lower end of said casing contracted to form a flange baffle, said housing adapted to contain a pool of oil, a plurality of baffle partitions for the casing, one of said baffles arranged to 50 form a restricted passage with the flange baffle, and the other baffles arranged to form conduits with the air outlet.

2. A dust collector comprising a housing, a lid, an air intake and outlet for the lid, an 55 inner casing open at both ends, the lower end portion of said casing contracted to form a flange baffle, said housing adapted to contain a pool of oil, a main baffle partition for the casing slanting downwardly from the 60 joinder of the air intake and outlet to form a restricted passage with the flange baffle, and a plurality of curved baffle partitions for the casing spaced apart to form conduits communicating with the outlet.

65 3. A dust collector comprising a housing,

a lid, an air intake and outlet for the lid, an inner casing open at both ends, the lower end portion of said casing contracted to form a flange baffle, said housing adapted to contain a pool of oil, a main baffle partition for the 70 casing slanting downwardly from the joinder of the air intake and outlet to form a restricted passage with the flange baffle, a plurality of curved baffle partitions for the casing spaced apart to form conduits communicating with the outlet, and said main and curved baffle partitions comprising a metal 75 backing and felt pads with apertured lath coverings arranged to form dust collecting pockets.

4. The combination with a motor vehicle and its carburetor of a dust collector comprising a housing, a lid, an air intake for the lid, an air outlet for the lid, a flexible conduit connecting said air outlet with the air intake of the carburetor, said housing adapted to contain a pool of oil, a main baffle partition arranged to direct the air from the air intake to the oil pool, a plurality of curved baffle partitions arranged to form conduits 80 communicating with the air outlet, and each of said baffles having a plurality of dust collecting pockets.

In testimony whereof I affix my signature.

ROY K. RUNYON.
